FIG-1

FIG-2

Hubert Seidl

INVENTOR

BY

Gifford + Scull

ATTORNEYS

UNITED STATES PATENT OFFICE.

HUBERT SEIDL, OF OBERHAUSEN, GERMANY, ASSIGNEE TO THE BABCOCK & WILCOX COMPANY, OF BAYONNE, NEW JERSEY, A CORPORATION OF NEW JERSEY.

FURNACE.

Application filed July 7, 1927, Serial No. 203,900, and in Germany March 17, 1926.

This invention relates to a furnace that is especially useful as a boiler furnace, and will be understood from the description in connection with the accompanying drawings in which Fig. 1 is a vertical section, partly broken away, of an illustrative embodiment of the invention, and Fig. 2 is a section along the line 2—2 of Fig. 1.

In the drawings, reference character 5 indicates the walls of a furnace that may be lined with highly refractory material in the usual way. As ash-pit is provided at the lower portion of the furnace with a sloping floor 6 and with a door 7 for removing the ashes. It has been found, especially with furnaces in which powdered fuel is burned, that when the doors are opened in order to remove ashes from the ash-pit, the sudden draft of cold air that enters interferes with combustion. By the present invention, this objection is overcome, so that combustion is kept satisfactory even when the ashes are being cleaned out.

A row 8 of water tubes that are slightly inclined to the horizontal extends across the lower portion of the furnace above the ash-pit and these tubes are connected to an inlet header 9 and an outlet header 10 which are located outside of the furnace walls and are connected, as by tubes 11 and 12, to the circulation system of the boiler. The inlet header 9 may be provided with a valved drain pipe 13. The tubes 8 are surrounded by long sleeves 15 that extend through one wall of the furnace and are revoluble upon the tubes 8. The sleeves 15 are provided with wings or plates 16 on opposite sides that extend across the furnace and are wide enough to overlap each other when the sleeves are turned into one position. Each sleeve may be provided with a bearing 17 at one end thereof in one wall of the furnace and is provided with a worm wheel 18 at the other end outside of the furnace. The worm wheels 18 mesh with a worm 19 that may be turned by any convenient means so as to cause the wings 16 to assume different positions.

A second row of slightly inclined tubes 20 may be located above the row 8 and in proximity to the same, these tubes 20 extending from an inlet header 21 to an outlet header 22, both of which are located outside of the

furnace walls and are connected to the circulation system of the boiler in any convenient manner.

The operation is as follows: In the normal operation of the furnace, the sleeves 15 carrying the wings 16 are turned by means of the worm 19 and gears 18 so that they will assume the positions shown in full lines in Fig. 2, thus permitting slag and ash to descend between the wings and collect at the bottom of the furnace upon the sloping floor 6. The water tubes 20 aid in protecting the wings by cooling the ash and slag as they descend between these tubes, and the water tubes 8 also cool the sleeves 15 and the wings 16. When it is desired to clean out the ashes and slag, the sleeves 15 are turned to bring the wings 16 into the dotted-line positions shown in Fig. 2, so that when the door 7 is opened, there will not be an inrush of air through the ash-pit into the combustion space of the furnace.

I claim:

1. In a furnace, water tubes in said furnace, a row of rotatable plates located above the ash-pit of said furnace, means for turning said plates so as to close the space above said ash-pit, said plates being mounted upon said tubes, and water tubes above said plates in proximity thereto.

2. In a furnace, a row of rotatable plates located above the ash-pit of said furnace, means for turning said plates so as to close the space above said ash-pit, and a set of water tubes above said plates between them and the combustion space of said furnace.

3. In a furnace for burning powdered fuel, a row of water tubes spaced apart and extending across the furnace above the bottom thereof to produce a cooling zone in the lower portion of the furnace chamber, connections whereby cooling water may be circulated through said tubes, and closure plates each rotatably mounted on one of said water tubes and arranged to be positioned vertically in the normal operation of the furnace and to be rotated to close the spaces between said water tubes to prevent passage of air into the furnace chamber above said tubes when the space below the tubes is opened to the air.

HUBERT SEIDL.
